UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,948, dated December 13, 1887.

Application filed November 10, 1887. Serial No. 254,871. Term of patent 3½ years.

To all whom it may concern:

Be it known that I, ELLEN MORAN, of the city, county, and State of New York, have invented and produced a new and original 5 Design for a Pattern of a Lady's Costume; and I do hereby declare that the engraved prints accompanying this specification convey to any one accustomed to using paper patterns a clear understanding of how a garment made up by 10 the pattern will appear.

The design shows a basque and a round walking-skirt. The skirt displays a long oval front drapery that falls to the edge of the skirt at the center, reveals the skirt to the belt at the 15 sides, and exhibits draping plaits and a long bournous loop in the top at either side of the center of the back; a lower back drapery that displays kilt-plaits flaring in fan fashion at its center, and a full upper back drapery that falls 20 straight to the edge below a long loose loop in each front edge, and is lifted to the top of

the lower drapery at the center by loopings. The basque displays a pointed plaited plastron upon the front reaching to the waist-line and framed at the sides by oval revers, a postilion 25 back that displays its skirt open at the center, coat-sleeves displaying elbow-sleeves deeply notched at the center of the upper side, and puffs extending from beneath the elbow-sleeves nearly to the wrist edges and exhibiting gath- 30 ers at its upper and lower edges, and a standing collar.

What I claim as my invention, and desire to secure by Letters Patent, is—

The design for a lady's costume, as shown 35 in the engraved prints accompanying this specification.

ELLEN MORAN.
